HASP LOCK

John Yanusko, Pottstown, Pa., assignor of one-half to Pete Bobovski, Parnassus, Pa.

Application February 23, 1934, Serial No. 712,672

4 Claims. (Cl. 70—5)

This invention relates to certain new and useful improvements in hasp locks, and the invention resides in the novel detail construction of the parts and the arrangement thereof.

5 The primary object of this invention is to provide a hasp lock having a sliding bolt adapted to engage the hasp member in order to lock a closure in a closed position.

A still further object of this invention is to 10 provide a hasp lock of the above mentioned character having spring retracting means and a tumbler spring pressed into engagement with a projection formed on the bolt.

A still further object of this invention is to 15 provide a hasp lock of the above mentioned character in which the lock construction is enclosed in a frame having suitable cut-out portions to receive the working parts of the lock and an external casing capable of being removed for the purpose 20 of making repairs to sections of the lock.

A still further object of this invention is to provide means between the lock frame and the external casing whereby the two will be locked together but may be unlocked by the use of an 25 instrument provided for this purpose.

A still further object of this invention is to provide a hasp lock of the above mentioned character having a peculiarly shaped tumbler protected from the key hole by means of a separate 30 partition mounted within the lock casing to prevent unauthorized persons from gaining access to the tumbler and operating the sliding bolt.

Other objects and advantages of the invention will become apparent during the course of the 35 following description forming a part of the specification and in which,

Figure 1 is a top elevational view of the hasp lock embodying this invention;

Figure 2 is a top elevational view of the same 40 showing the hasp hingedly connected to a closure and the manner in which the lock on the end thereof is positioned for engaging and receiving the eye loop;

Figure 3 is an enlarged fragmentary top elevational view of the lock per se;

Figure 4 is a longitudinal cross-sectional view 45 taken on line 4—4 of Figure 2, looking in the direction of the arrows illustrating the construction of the two-part casing and showing the sliding bolt to which is presented the unique tumbler;

Figure 5 is a similar cross-sectional view illustrating the bolt in its retracted position, only a fragmentary portion of the lock structure is shown to illustrate this feature;

50 Figure 6 is a longitudinal cross-sectional view

taken on line 6—6 of Figure 1, looking in the direction of the arrows illustrating the construction of the lock casing and further illustrating the manner in which the sliding bolt is projected into its locked position with the keeper;

Figure 7 is a transverse cross-sectional view 55 taken on line 7—7 of Figure 3, looking in the direction of the arrows, further illustrating the locked casing construction and showing the sliding bolt as projected into its locked position with the hasp keeper; and

Figure 8 is a similar transverse cross-sectional view taken on lines 8—8 of Figure 4 looking in the direction of the arrows illustrating the manner in which the sliding bolt is held in its locked 70 position by means of the spring pressed plunger type tumbler and showing the manner in which the spring acting upon the plunger or tumbler is employed for locking the two-parts of the casing 75 together.

In the drawing, the reference character A designates a hinged closure such as a door or the like which swings into abutment with a door frame B.

Secured to the door frame B is a plate 5 having a 80 hasp loop 6 which is of ordinary construction and is adapted to be received within an opening 7 formed in a hinged hasp leaf 8 preferably formed of strap iron and tapering from the end 9 to a reduced portion 10 so that the free end may be 85 bent into a loop as at 11 for being received between a pair of upstanding ears 12 formed on a securing plate 13. A bolt 14 is passed through the opening 15 formed in the ears 12 and extends through the loop 11 thereby allowing the hasp 90 hinge 8 to swing about the pivot or bolt 14.

Secured to the free swinging end of the hinge leaf hasp 8 is a two-part lock casing including a metal block 16 having a transverse slot 17 registering with the slot 18 formed in the free swinging 95 end of the hinged hasp leaf 8. Formed at right angles to the slot 17 and on opposite sides thereof are bores 19 and 20 for slidably receiving a locking bolt 21 having formed intermediate its ends a projection 22 adapted to engage a locking tumbler which will be hereinafter fully described. Directly opposite the projection 22 is a projection 23 terminating in a circular portion adapted to travel in a bore 25 formed in the block 16, which bore extends from the center portion of the locking casing to one end thereof and terminates inwardly as at 26 which forms an abutment for one end of a coil spring 27 which has its opposite end impinging upon the circular portion 24 of the projection 23 whereby the bolt 21 will be normally 100

105 impinged upon the circular portion 24 of the projection 23 whereby the bolt 21 will be normally 110

retracted from its locking position within the hasp loop 6.

It will be noted that the block 16 is slotted as at 28 and 29 on opposite sides of the sliding bolt 21 for receiving the projections 22 and 23 along with the disk-like portion 24 whereby the bolt 24 may slide freely within the lock casing unless otherwise disturbed.

It is intended to secure the block 16 to the free end of the hinged hasp by means of bolts 30 extending therethrough or if desired, the block 16 may be welded or otherwise rigidly secured to the hinge hasp 8.

Directly at right angles to the bore 20 formed in the casing block 16 is a bore 31 for slidably receiving a tumbler block 32 having a laterally extending portion 33 offset from the sliding tumbler block 32. A partition 34 extends upwardly into the bore 31 upon which the tumbler block 32 may rest when the parts are in their locked position. A key hole slot 35 is formed in one face of the block 16 whereby the ward on a key 36 may engage the tumbler block 32 for the purpose of shifting the tumbler block against the tension of a coil spring 37 to unlock the sliding bolt 21 whereby the coil spring 27 will retract the bolt 21 from its locked position.

It will be noted that the coil spring 37 has one of its ends engaging the tumbler block 32, while the opposite end extends through the bore 31 and is received in a cut-out portion 38 formed in a rectangular box-like casing 39 which may be slipped over the block 16 and secured in place by means of bolts 40 extending through the rectangular box-like casing 39 and being anchored in the hinged hasp leaf 8.

Formed on opposite sides of the sliding connection between the lock casing block 16 and the rectangular box-like casing 39 are openings 41 and 42 in direct communication with the bore 31 for allowing the insertion of an instrument or tool to engage the coil spring 37 in order that the coil spring may be moved to allow displacement of the box-like casing 39 from the block 16.

One end of the sliding bolt 21 projects through the end of the block 16 and also through the opening 44 in the box-like casing 39 and said sliding bolt 21 is further guided by means of a projection 45 formed on the free swinging end of the hasp leaf 8 having an opening 46. The projection 45 also forms an abutment for the outer box-like casing 39 for holding the same against longitudinal displacement.

A cover plate 48 may be held in place by the bolt 40 and said cover plate 48 is provided with a key hole opening 49 adapted to register with the key hole slot 35 formed in the block 16. A handle 50 may be secured to the cover 48 for the purpose of swinging the entire structure about the pivot 14 after the bolt 21 has been retracted from its locking position to move the free end of the swinging hasp hinge 8 out of engagement with the hasp loop 6.

It is to be understood that the form of the invention herewith shown and described is to be taken as a preferred embodiment of the same and that various changes in the shape, size and arrangement of parts may be resorted to without departing from the spirit of the invention or the scope of the sub-joined claims.

I claim:—

1. In a lock of the character described, a hinged hasp, a lock member on the swinging end thereof, a sliding bolt in the lock member, diametrically opposite projections carried by the

bolt, a spring associated with one projection for retracting the bolt to its released position, a spring pressed locking tumbler engageable with the other projection for holding the bolt in locked position in engagement with a keeper, the lock member including a block having openings therein for the lock mechanism, a rectangular casing inclosing the block and a cover overlying the block and rectangular casing.

2. In a lock of the character described, a hinged hasp, a lock member on the swinging end thereof, a sliding bolt in the lock member, diametrically opposite projections carried by the bolt, a spring associated with one projection for retracting the bolt to its released position, a spring pressed locking tumbler engageable with the other projection for holding the bolt in locked position in engagement with a keeper, and the axes of the operating forces of the bolt retracting and tumbler operating springs being at right angles to each other the lock member including a block having openings therein for the lock mechanism, a rectangular casing inclosing the block and a cover overlying the block and rectangular casing.

3. In a lock of the character described, a hinged hasp, a lock member on the swinging end thereof, a sliding bolt in the lock member, diametrically opposite projections carried by the bolt, a spring associated with one projection for retracting the bolt to its released position, a spring pressed locking tumbler engageable with the other projection for holding the bolt in locked position in engagement with a keeper, the lock member including a block having openings therein for the lock mechanism, a rectangular casing inclosing the block and a cover overlying the block and rectangular casing, the opening in the block for the support of the spring pressed tumbler extending through a side of the block, the adjacent casing wall having a recess therein registering with the last named opening with the tumbler spring extending into the recess on the upper edge of the casing and adjacent portion of the cover being cut away to expose the spring for manual retraction whereby the rectangular casing may be removed from the block to permit access to the tumbler.

4. In a lock of the character described, a hinged hasp, a lock member on the swinging end thereof, a sliding bolt in the lock member, diametrically opposite projections carried by the bolt, a spring associated with one projection for retracting the bolt to its released position, a spring pressed locking tumbler engageable with the other projection for holding the bolt in locked position in engagement with a keeper, and the axes of the operating forces of the bolt retracting and tumbler operating springs being at right angles to each other, the lock member including a block having openings therein for the lock mechanism, a rectangular casing inclosing the block and a cover overlying the block and rectangular casing, the opening in the block for the support of the spring pressed tumbler extending through a side of the block, the adjacent casing wall having a recess therein registering with the last named opening, with the tumbler spring extending into the recess on the upper edge of the casing and adjacent portion of the cover being cut away to expose the spring for manual retraction whereby the rectangular casing may be removed from the block to permit access to the tumbler.

JOHN YANUSKO.
